John D. Buckingham, Chicago, Ill., assignor to Lucien Lelong, Inc., Chicago, Ill., a corporation of Illinois

Application April 2, 1945, Serial No. 118,825

Term of patent 14 years

(Cl. D58—6)

To all whom it may concern:

Be it known that I, John D. Buckingham, a citizen of the United States and a resident of the city of Chicago, in the county of Cook and State of Illinois, have invented a new, original, and ornamental Design for a Perfume Bottle or Similar Article, of which the following is a specification, reference being had to the accompanying drawing forming a part thereof.

On the drawing:

Figure 1 is a front elevational view of the perfume bottle or similar article, showing my new design, the back of the bottle being substantially plain.

I claim:

The ornamental design for a perfume bottle or similar article, as shown and described.

JOHN D. BUCKINGHAM.
